UNITED STATES PATENT OFFICE.

MATTHIAS N. FORNEY, OF NEW YORK, N. Y.

FLUID-PRESSURE ENGINE.

SPECIFICATION forming part of Letters Patent No. 741,782, dated October 20, 1903.

Application filed July 2, 1903. Serial No. 164,047. (No model.)

To all whom it may concern:

Be it known that I, MATTHIAS N. FORNEY, of the borough of Manhattan, in the city and State of New York, have invented a certain 5 new and useful Improvement in Fluid-Pres-
sure Engines, of which improvement the fol-
lowing is a specification.

My present invention is an improvement on that set forth in Letters Patent of the 10 United States, No. 489,648, granted and issued to me under date of January 10, 1893, and is more particularly designed for application to compound steam-engines, but is applicable to other fluid-pressure and to binary engines 15 which are not compound; and its object is to facilitate and further improve the means whereby the reciprocating elements of engines of such character are made to counter-
balance each other by a more convenient dis-
20 position of their parts, which results in a re-
duction of cost of the engine, and, further,
by locating the two cylinders in line one with
the other, so that their axes are coincident.
The centers of gravity of their two pistons 25 then both traverse a common axis, and thus
the disturbing action caused by their move-
ment in two different planes is avoided.

The improvement claimed is hereinafter
fully set forth.

30 In the compound engine set forth in Letters Patent No. 489,648 aforesaid the piston-rod of the low-pressure cylinder is directly connected to what is termed a "primary" lever, which is in turn articulated to a pair of "sec-
35 ondary" levers, which oscillate in journals or trunnions supported in fixed bearings, the system of levers forming a "parallel motion," which constrains the piston-rod to move in a straight line. In this construction the axes 40 of the journals or trunnions of the secondary levers are in a plane which coincides with the axis of one of the cylinders, which is the line in which the center of its piston-rod moves. The piston-rod of the high-pressure piston is 45 connected to the lower end of the secondary lever; but as these move in a path which is an arc of a circle to secure rectilineal move-
50 ment of this piston-rod it requires to be and is shown as connected to the levers by means of a guide, cross-head, and short links. The other two cylinders are located with their axes in two planes some distance apart, and con-

sequently the movement of the pistons in op-
posite directions to each other exerts a turn-
ing action in the mechanism which to a cer- 55
tain extent is a source of disturbance.

Under my present invention the axes of the two cylinders are made coincident by locating the cylinders in line one with the other. The piston-rods of each cylinder are then con- 60
nected to separate primary levers which are articulated to opposite ends of a pair of sec-
ondary levers, so that all the piston-rods are constrained to move in straight lines. By 65
this means the guides, cross-head, and short connecting links of Patent No. 489,648 are wholly dispensed with, and as the centers of gravity of the two pistons move in the same line no turning action or consequent disturbance is exerted thereby.

70 In the accompanying drawings, Figure 1 is a vertical transverse central section through a vertical two-cylinder compound engine of the overhead marine type illustrating an embodiment of my invention, the cylinders being located in line one with the other and therefore having a common axis; Fig. 2, a vertical longitudinal central section through the same; and Figs. 3 and 4, horizontal sec-
75
tions on the lines *a a* and *b b*, respectively, 80
of Fig. 1.

The drawings illustrate the application of my invention in a compound engine of the vertical overhead marine type, although it will be obvious that the cylinders may be lo- 85
cated horizontally or in an inclined position, if desired. It will be understood, as has al-
ready been explained, that if the pistons of two cylinders which are in different planes are connected to a system of oscillating le- 90
vers, so that the pistons move in relatively opposite directions, their opposite movements will exert a turning action on the mech-
anism, which is to a certain extent a source of disturbance. This may to a very consider- 95
able extent be compensated by the employ-
ment of a supplemental counterweight, as set forth in Letters Patent of the United States, No. 701,477, granted and issued to me under date of June 3, 1902, but can be com- 100
pletely eliminated by the construction herein shown, in which the high-pressure cylinder 1^a is located below and in line with a low-
pressure cylinder 1, the axes of the two cyl-

inders being therefore coincident. The centers of gravity of the pistons consequently traverse in the same straight line, and therefore when moving in opposite directions they 5 do not exert any turning action on the mechanism or produce the disturbance before referred to. In order that the pistons may move in opposite directions, they are connected with the connecting-rod and crank-pin 10 through the intermediation of an oscillating-lever system, the detailed features of which mechanism will now be explained.

The high-pressure cylinder 1^a and the low-pressure cylinder 1, which is located above 15 and axially coincides with the high-pressure cylinder, are secured to housings or standards 55, fixed upon a bed-plate 56, which supports the main bearing of the crank-shaft 19 of the engine, a suitable head 1^b being interposed between the two cylinders. The high-pressure cylinder is fitted with a piston 2^a of the usual form, which is fixed upon a piston-rod 3^a, to the outer end of which is secured a forked head 48, which is coupled by 25 a pin 15^a to the inner arms of a pair of primary levers 7 7, these being two parallel lever-bars. The outer arms of the primary levers 7 7 are coupled by a pin 9 to a radius-link or pair of radius-links 11 11, the opposite 30 ends of which are coupled to a pin 10, fixed to the housings 55. The low-pressure cylinder 1 is fitted with a piston 2, which is fixed upon two piston-rods 3 3, projecting through suitable stuffing-boxes 1^c 1^c and having their 35 outer ends coupled by pins 15 15 to the inner arms of a pair of second primary levers 7^a 7^a. The outer arms of the second primary levers 7^a are, similarly to those of the primary levers 7, coupled by a pin 9^a to a pair of radius-links 11^a 11^a, the opposite ends of which are 40 coupled to a pin 10^a, fixed to the housings 55. The primary levers 7 and second primary levers 7^a are coupled intermediately of their ends to a pair of secondary levers 8 8, 45 which are parallel lever-bars having central journals 13, fitting in fixed bearings 14, the swiveling connection of the secondary levers to the primary levers 7 being effected by a pin 12 and that to the second primary levers 50 by a pin 12^a. The main connecting-rod 4 is coupled at its upper end to the forked head 48 of the high-pressure piston-rod and to the primary levers 7 by the pin 15^a, and its lower end is coupled to the crank-pin 18 of the 55 crank-shaft 19.

It will be obvious to those skilled in steam-engine construction that two piston-rods are shown as employed in the upper low-pressure cylinder 1 for the purpose merely of equalizing the stresses upon opposite sides of its center and that the ordinary expedient of a single piston-rod, passing out of the top of the cylinder and fixed to a cross-tail, from which two exterior connections extend to the 60 second primary levers 7^a, would be the mechanical equivalent of the specific two-piston-rod construction herein described and

shown and could be substituted therefor in the discretion of the constructor without departure from the spirit or operative principle 70 of my invention. It will also be seen that my invention is not limited in application to an engine having two cylinders only, as three or more cylinders located one beyond the other with their axes on a common center 75 line might, if desired, be employed, the pistons of two of the cylinders moving coincidentally in one direction and the other piston or pistons moving in the opposite direction.

The operation of the high-pressure piston, 80 piston-rod, and connecting-rod is similar to that of the corresponding parts in engines of the ordinary construction; but the piston-rods are constrained to move in straight lines by the system of oscillating levers, which 85 constitutes a parallel motion. The low-pressure piston being connected by its two piston-rods to the second primary levers 7^a, the pressure exerted upon it is transmitted by said levers to the secondary levers 8 8 and by them 90 to the primary levers 7 7 and thence to the forked head 48, connecting-rod 4, and crank-pin 18. The levers are so proportioned that the inner ends of the primary levers and second primary levers move in substantially 95 straight lines, and these levers serve as guides for the piston-rods or both the high and the low pressure cylinders.

Any suitable and preferred form of valve mechanism may be employed for admitting 100 motive fluid to the high-pressure cylinder, conducting it thence to the low-pressure cylinder after it has exerted its pressure on the high-pressure piston, and finally exhausting it from the low-pressure cylinder after it has 105 been expanded and done its work therein. In the instance exemplified the high-pressure distribution-valve 25^a and the low-pressure distribution-valve 25 are each of the end-admission piston type and control induction and 110 education ports and passages of the ordinary form in the high-pressure and low-pressure cylinders, respectively. The valves 25^a and 25 are fixed upon a common valve-stem 28 and are fitted to coincidentally reciprocate 115 therewith in a valve-chest 35^b, adjoining the cylinders, to which chest motive fluid is admitted through a supply-pipe 20^a and from which it is finally exhausted through an exhaust-pipe 23^a. The valve-stem 28 passes 120 through a stuffing-box in the valve-chest and is coupled at its outer end to one of the arms 32 of a double-armed rock-shaft 29, journaled in bearings on the housings 55. Movement may be imparted to the opposite arm 30 of the 125 rock-shaft 29 by any suitable and preferred valve-gear, as a single eccentric, either fixed or adjustable, or a pair of eccentrics and a shifting link. Mechanism for this purpose being familiar to those skilled in the art and 130 not constituting in and of itself any part of my present invention, it is not herein in detail set forth.

As the connection of the two pistons with

the oscillating-lever system requires them to work in opposite directions one to the other, the movement of one piston and its rod will exactly balance that of the other if they are 5 of equal weight.

The form of engine illustrated while more particularly designed for marine or stationary purposes may obviously be applied to use in locomotive-engines or automobiles without 10 variation of its operative principle.

I claim as my invention, and desire to secure by Letters Patent—

1. In a fluid-pressure engine, the combination of two cylinders located one beyond the other with their axes on a common center 15 line, a piston and piston-rod in one cylinder, a piston and piston-rod in the other cylinder, a system of oscillating levers forming "parallel motions," connected to the piston-rods 20 and adapted to constrain the piston-rods of the two cylinders to move in straight lines and in relatively opposite directions, a driving-shaft, a crank thereon, and a main rod connecting the oscillating-lever system with 25 the crank.

2. In a fluid-pressure engine, the combination of two cylinders located one beyond the other with their axes on a common center line, a piston and piston-rod in one cylinder, 30 a piston and a pair of piston-rods in the other cylinder, a system of oscillating levers comprising a primary lever articulated, at one

end, to the piston-rod of one cylinder and having a movable fulcrum at its opposite end, a pair of primary levers articulated, at one 35 end, to the piston-rods of the other cylinder and having movable fulcrums at their outer ends, and secondary levers, articulated to the primary levers, and journaled centrally in fixed bearings, a driving-shaft, a crank thereon, and a main rod connecting the oscillating-lever system with the crank.

3. In a fluid-pressure engine, the combination of two cylinders located one beyond the other with their axes on a common center 45 line, a piston and piston-rod in one cylinder, a piston and a pair of piston-rods in the other cylinder, a primary lever articulated at one end to the piston-rod of one cylinder, a radial link coupled to said primary lever and to a 50 fixed pivot, a pair of primary levers articulated at one end to the piston-rods of the other cylinder, radial links coupled to said primary levers and to a fixed pivot, secondary levers, 55 articulated to the primary levers, and journaled centrally in fixed bearings, a driving-shaft, a crank thereon, and a main rod connecting the oscillating-lever system with the crank.
